ATTEST:

James Thiverry,
A. J. Sprague.

INVENTOR:

A. J. Sprague
Per Attorney
A. J. Sprague

United States Patent Office.

ANDREW J. SPRAGUE, OF TOLEDO, OHIO.

Letters Patent No. 105,270, dated July 12, 1870.

IMPROVED BRICK-REPRESSING MACHINE.

The Schedule referred to in these Letters Patent and making part of the same.

To whom it may concern:

Be it known that I, ANDREW J. SPRAGUE, of Toledo, in the county of Lucas and State of Ohio, have invented a new and useful Improvement in Machines for Repressing Brick; and I do declare that the following is a true and accurate description thereof, reference being had to the accompanying drawing and to the letters of reference marked thereon, and being a part of this specification.

Figure 1 is a side elevation:

Figure 2 is a vertical cross-section, showing the position of the working parts, and a brick just ready to move forward upon the apron to the press.

Figure 3 is a section, showing the brick in the process of being pressed.

Figure 4 is also a section, showing the manner in which the brick is released after being pressed.

Like letters indicate like parts in each figure.

The nature of this invention relates to the construction of an apparatus for repressing brick after they have been molded in any ordinary manner, when they are required for front or outside work, where perfect uniformity in size, and square and true corners and edges are desired.

The invention consists in a new and ingenious arrangement of well-known mechanical devices, and their peculiar application to produce the purpose desired.

In the accompanying drawing—

A represents a suitable frame-work, which sustains the working parts of the apparatus.

B represents a shaft, whose ends are properly journaled into the opposite sides of the frame A, and receives motion from the geared wheels C, or any other suitable means.

D are cams, rigidly secured to said shaft B for the purpose, in the rotation of the shaft, of raising the mold-box E, by means of the downward-projecting arms a, whose lower extremities are provided with suitable friction-wheels b, which engage with and travel upon the face of the cams D.

F is another cam, also rigidly secured to the centre of the length of said shaft B, and is of a peculiar shape, as shown, and provided with a prolongation, c, for the purpose hereinafter described.

This cam, in the rotation of the shaft B, gives an upward motion to the connecting-rod G, the lower end of which is provided with wheel or friction-roller d, which engages with and travels upon the face of the cam F, while its upper end is secured to the bed H.

I is a yoke, supported by and secured to the frame A by means of the threaded bolts e and nuts f, and, by means of the same devices, said yoke may be raised or lowered, as desired.

To the under side of this yoke is secured the fixed

platen J, the face of which should be the size of the surface of the brick, and should fill the mold-box E.

The lower face of this platen is covered by a sheet of rubber, g, secured at its two ends in any appropriate manner.

Some holes, h, pass vertically through the platen, and coincidentally through the rubber sheet, for the purpose of letting any surplus clay out of the mold-box.

Other holes, i, four or more in number, also pass vertically through the said platen, near its corners, for the purpose hereinafter explained.

R is a drum, properly journaled between the sides of the frame A and its shaft, provided with a spider, K, rigidly secured thereto.

The face of the drum is provided with spurs, k, projecting slightly from its periphery, for the purpose of compelling, in the rotation of said drum, the endless apron L to advance with the said rotation.

Motion is communicated to said drum by means of the projecting arm l, which is secured to the geared wheel C, and, in its rotation, engages with one of the arms of the spider, and rotates it until released from said engagement, thereby giving an intermittent rotary motion to the drum.

Said endless belt or apron L is made of coarse strong canvas, for the purpose of roughening, by indentation of its threads, into the lower surface of the bricks, the more effectually to enable the mortar with which they may be laid to hold.

The apron passes around the drum and the rollers M, which are so arranged, relatively to each other, that the apron is easily rotated; as desired, to carry the brick into the press, and out from the same after they have been pressed.

Should it be deemed preferable, any other suitable material may be used for this apron or belt, such as leather or rubber.

In the operation of this apparatus, a brick is placed upon the apron, with one end and side next the guides m, the mold-box resting upon said apron.

In the rotation of the crank and shaft the bed is raised, carrying up with it the mold-box, the platen entering said mold-box from the top. In the continued rotation of the machine, the bed descends, leaving the mold-box up against the yoke.

The projection on the geared wheel then engages with an arm of the spider, and partially rotates the drum and apron, which carries the brick to its proper position under the mold-box, which descends and encloses it, the brick resting upon the apron, immediately over the center of the bed.

It will be seen that after the brick has been pressed the bed falls but a little way, while the atmospheric

pressure admitted to the upper side of the rubber sheet deflects the same, and compels the brick to drop on to the apron, when the prolongation of the cam allows the bed to drop to place ready to receive another brick, while that already pressed is passed out at the opposite side, in the same movement of the apron.

What I claim as my invention, and desire to secure by Letters Patent, is—

The combination of the frame A, shaft B, cams D

F, mold-box E, connecting-rod G, bed H, yoke I, platen J, spider K, apron L, rollers M, and drum R, when constructed, arranged, and operating substantially as and for the purposes herein described, set forth, and shown.

ANDREW J. SPRAGUE.
